(57) **CLAIM**

I claim the ornamental design for an automotive wheel, as shown and described.

DESCRIPTION

FIG. 1 is perspective view of an automotive wheel, embodying my new design;

FIG. 2 is a cross-sectional view thereof, taken along line 2-2 in FIG. 3; and,

FIG. 3 is a front view thereof.

The broken lines show features of the automobile wheel that form no part of the claimed design. The dot-dot-dash lines represent boundaries of the claimed design, and form no part of the claimed design. The dot-dot-dash outer boundary lines of the upper rim shown in FIG. 2 are unclaimed outer boundary lines. The dashed outer boundary lines of the lower rim are unclaimed and extend from the dot-dot-dash outer boundary lines of the upper rim. The recessed surface of the automobile wheel on which the central opening and six lug holes are shown in FIG. 1 is unclaimed. The outer circular dot-dot-dash line that surround the recessed surface is an unclaimed boundary line between the claimed upper rim and the unclaimed recessed surface. The cross-sectional surface shown in FIG. 2 includes solid hatching lines associated with claimed upper rim and dashed hatching lines associated with unclaimed lower rim.
